UNITED STATES PATENT OFFICE.

WILLIAM DOUGLASS WOODWARD, OF PLATTSBURG, NEW YORK, ASSIGNOR
OF ONE-HALF TO ANNA S. HARRINGTON, OF SAME PLACE.

RAILWAY-SWITCH.

SPECIFICATION forming part of Letters Patent No. 367,882, dated August 9, 1887.

Application filed December 7, 1886. Serial No. 220,872. (No model.)

To all whom it may concern:

Be it known that I, WILLIAM DOUGLASS WOODWARD, of Plattsburg, in the county of Clinton and State of New York, have invented 5 a new and useful Improvement in Railroad-Switches; and I hereby declare the following to be a full and clear description thereof.

The object of this invention is to construct a railway-switch in such a manner that the 10 switch-rails may be operated or thrown from one track to another, either from the ground or from the top of a car on the train, without the necessity of the switchman leaving the train.

15 The invention will be readily understood by reference to the accompanying drawings, of which—

Figure 1 is a general plan of a main and a side track fitted with my improved switch. 20 Fig. 2 is a side elevation of the same. Fig. 3 is a transverse sectional elevation showing the mechanism for operating the switch from the cars. Fig. 4 is a section on line xx of Fig. 1.

The rails A indicate the main track and the 25 rails A' the side track. The rails are secured to tie-pieces a in the usual manner. The guard-rails A ^{2} are constructed and applied in the usual manner. The switch-rails A ^{3} are different from those in common use, in that 30 they are made wedge-shaped in plan, and at their wider ends they are pivoted to a tie, a , by means of a sound central pin, a' , as shown clearly in Fig. 1. The small end of the said wedge-shaped switch-rail is adjusted in form 35 and position to lie tightly against the inside of the contiguous main rail, so as to shunt the train onto it, when it is so placed in contact with the main-rail, as in the ordinary form of operating switching-rails. An operating- 40 lever, B, is pivoted by a bolt, b , to one of the ties a in a suitable position to operate the switch-rails A ^{3} , with which its free or swinging end is connected by a switch-rod, B', as shown clearly in Fig. 1. This operating-lever 45 B is placed about midway between the rails to be operated upon, and is placed parallel, or nearly so, with the said rails. The said switch-rod B' holds the moving or sharpened ends of the switch-rails at a distance apart slightly

less than the gage of the road, as shown in 50 Fig. 1, and as is customary, so as to allow for the said switching-rails to be moved to or from either side, so as to make continuous either the rails of the main track or of the side track.

Outside of the rails of the track and lying 55 parallel therewith, and preferably fastened to the ends of the ties, (though this is not essential,) are placed conduit-pipes C for each side of the track. These may be formed of ordinary gas-pipes and joined together in a manner similar to the joinings of gas-pipe. One end of each of these conduit-pipes is made to terminate opposite the switch-rod B' in a quarter-turn-elbow, C'. From this elbow-turn the conduit-pipe is continued for some distance—several hundred feet, if desired—to an upwardly-turned elbow, C ^{2} , from which said vertical elbow a riser-pipe, C ^{3} , extends upwardly to a point above the level of the top of the train, and there connects with a laterally-turned elbow, C ^{4} . These two upper elbows C ^{4} are made to face each other, and are connected by a lateral pipe, C ^{5} , placed transversely over the top of the track, just above the headway on top of the train. The two vertical riser-pipes C ^{3} should be well braced by 60 means of suitable stays or braces, c.

An operating-cord, D, preferably of wire rope, is run through the conduit-pipe at each 65 side of the track, and one end passing out at the elbow C' is attached to the contiguous end of the switch-rail A ^{3} , and thence extending through the said conduit-pipes, as above described, debouches therefrom at a convenient point in the pipe C ^{5} directly over the top of 70 the cars passing thereunder, and thence hangs down a short distance and terminates in a ring, D', placed so any of the train-hands can easily reach and pull it, so as to move and adjust the switch-rails as desired without leaving the 75 train. At the points where the operating-ropes leave the transverse pipe C ^{5} sheaves d should be attached to the said pipe so as to ease the operating-cord in its movements.

Having described my invention, I claim— 80
1. The switch-rails of a railway-track, 85 coupled together by a transverse operating-rod and operated by operating-cords attached,

respectively, to the moving ends of the switch-rails, and conducted thence through conduit-tubes to points placed at some distance from the switch-rails and above the tracks, and 5 within reach of the trainmen, substantially as described.

2. The switch-rails A³, connecting-rod B', operating-cords D, and the handles D', and the

guiding-tubes C, C', C², C³, C⁴, and C⁵, combined and arranged substantially as described. 10

In witness whereof I have hereunto set my hand in presence of two witnesses.

WILLIAM DOUGLASS WOODWARD.
